DESIGN FOR A HANDBAG

Leo Freidman, New York, N. Y., assignor to Gold Seal Importers, Inc., New York, N. Y., a corporation of New York

Application June 21, 1940, Serial No. 93,165

Term of patent 7 years

To all whom it may concern:

Be it known that I, Leo Freidman, a citizen of the United States and residing at New York, in the county of New York and State of New York, have invented a new, original, and ornamental Design for Handbags, of which the following is a specification, reference being had to the accompanying drawing, forming part thereof, and in which:

Fig. 1 is a front elevational view of a handbag showing my new design; and

Fig. 2 is a top plan view thereof.

The salient feature of the invention resides in the rope-like conformation made of the bag fabric and from which the irregularly pleated areas of bag fabric extends.

I claim:

The ornamental design for a handbag, substantially as shown and described.

LEO FREIDMAN.
